(57) **CLAIM**

The ornamental design for cartoon kit of atomization electronic cigarette, as shown and described.

DESCRIPTION

FIG. 1 is the front elevational view of cartoon kit of atomization electronic cigarette;

FIG. 2 is the rear elevational view thereof;

FIG. 3 is the right side elevational view thereof;

FIG. 4 is the left side elevational view thereof;

FIG. 5 is an enlarged top plan view thereof;

FIG. 6 is an enlarged bottom plan view thereof; and,

FIG. 7 is a perspective view thereof.

The broken lines in FIGS. 2, 3 and 4 as illustrating portions of the lipstick type of atomization electronic cigarette that form no part of the claimed design.
